ORNAMENTATION OF BARBERS' CHAIRS.

No. 17,283.

Patented Apr. 26, 1887.

UNITED STATES PATENT OFFICE.

THEODORE A. KOCHS, OF CHICAGO, ILLINOIS.

DESIGN FOR THE ORNAMENTATION OF BARBERS' CHAIRS.

SPECIFICATION forming part of Design No. 17,283, dated April 26, 1887.

Application filed March 10, 1887. Serial No. 230,473. Term of patent 7 years.

To all whom it may concern:

Be it known that I, THEODORE A. KOCHS, a citizen of the United States of America, residing at Chicago, in the county of Cook and State of Illinois, have invented a certain new and original Design for a Barber's Chair, of which the following is a specification, reference being had therein to the accompanying drawing, forming part thereof.

10 The drawing represents a perspective view of a barber's chair having my new design, which consists in the ornamentation of the chairs by the representation of a dragon on the face of the seat side rails of the frame of the chair, the curved neck and head of the dragon being on the forward protuberating end that forms the base for the front standards of the arm-rests, his winged body being on about the middle of the seat-rail, with his coiled serpentine tail extending toward the back of the chair and his feet, in shape of arabesque leaves, ex-

tending downward on the side of the upper portions of the front legs of the chair.

In the illustration, A denotes the seat-rail, B the front leg, and C the arm-rest standard, 25 of the barber's chair; and *a* designates the head, *b* the neck, *c* the winged body, *d* the tail, and *e* the arabesque leaves as feet of the representation of the dragon.

What I claim is--

30 The design for the ornamentation of a barber's chair, consisting in the representation of a dragon upon the seat side rails thereof, with the feet of the dragon, in shape of arabesque leaves, extending downward on the side of the 35 front legs of the chair, as set forth.

In testimony whereof I affix my signature in presence of two witnesses.

THEODORE A. KOCHS.
